US00D684556S

(12) **United States Design Patent**
Kim et al.

(10) **Patent No.:** **US D684,556 S**
(45) **Date of Patent:** **** Jun. 18, 2013**

(54) **HANDHELD ELECTRONIC DEVICE**

(71) Applicant: **Research In Motion Limited**, Waterloo (CA)

(72) Inventors: **Younghwan Kim**, Kitchener (CA); **Marco Sixtus Ferrari**, Waterloo (CA); **Todd Andrew Wood**, Toronto (CA); **Brian Dennis Paschke**, Toronto (CA); **Di Tao**, Toronto (CA); **Ingve Holmung**, Toronto (CA); **Jamaal Peele**, Mississauga (CA); **Wei He**, Kitchener (CA); **Anders Fahrendorff**, Ottawa (CA); **Jodie Elizabeth Fletcher**, Ottawa (CA); **Cortez Corley**, Waterloo (CA); **Roman Peter Rak**, Waterloo (CA); **Aaron Michael Szymanski**, Mississauga (CA)

(73) Assignee: **Research In Motion Limited**, Waterloo, Ontario (CA)

(**) Term: **14 Years**

(21) Appl. No.: **29/438,517**

(22) Filed: **Nov. 30, 2012**

(51) LOC (9) Cl. **14-03**

(52) U.S. Cl.

USPC ..... **D14/138 AA**; D14/346

(58) **Field of Classification Search**

USPC ..... D14/138 AA, 138 R, 496, 341, 345, D14/346, 203.1, 203.4, 203.7, 147, 248; D21/517; 455/575.1, 556.2, 556; 379/433.01, 379/433.04; 361/679.3, 679.56
